UNITED STATES PATENT OFFICE.

ARTHUR A. CRAIG, OF CHICAGO, ILLINOIS.

WINDOW VENTILATOR.

Application filed September 16, 1921. Serial No. 501,083.

To all whom it may concern:

Be it known that I, ARTHUR A. CRAIG, a citizen of the United States, residing at Chicago, in the county of Cook and State of Illinois, have invented a certain new and useful Improvement in Window Ventilators, of which the following is a full, clear, concise, and exact description, reference being had to the accompanying drawings forming 10 a part of this specification.

My invention relates to window ventilators and is an improvement over the device disclosed in my co-pending application Serial No. 427,695, filed December 2, 1920.

15 My improved ventilator is intended for use in window frames, though it will be apparent that the device has utility in any place where controlled ventilation is desirable.

20 Window ventilators, as constructed heretofore, are adapted for insertion in a window frame, and in order to compensate for variation in size, they are constructed to be extensible. A large majority of these devices interfere with opening and closing of the window, while many have proposed the use of various locking devices for holding the ventilator in the window frame. A cumbersome and expensive construction has been 25 the result, which has greatly retarded the extensive use of window ventilators.

30 In my prior application, provision has been made for causing the ventilator to be selflocking in the window frame, without interfering with the window. This is accomplished by the use of material which, of its very nature, is compressible. Thus pressing it in place, by extending the length, securely locks the ventilator in place.

35 In the present invention, I propose to improve the construction of this device by mounting upon each end thereof strips of material having an exceptionally high gripping ability. The provision of vertical reinforcing strips at each end of the ventilator 40 serves as means for acquiring an increased gripping surface without making the device cumbersome.

45 One of the main objects of this invention is to obtain a ventilator of the simplest construction, which may be cheaply and quickly produced, and which will securely hold itself in position, directing the incoming air upwardly and preventing drafts occurring 50 at the points of engagement or between the panel members.

In the accompanying drawings in which I have illustrated one embodiment of my invention, Figure 1 is a fragmentary isometric view of a window frame having a 60 ventilator embodying my invention inserted therein;

Figure 2 is an elevational view of the side of the ventilator opposite to that shown in Figure 1;

Figure 3 is a top edge view of the same,

Figure 4 is a fragmentary end detail of the ventilator,

Figure 5 is a section taken on line 5—5 of Figure 2,

Figure 6 is a detail view showing the manner of fastening the end reinforcing strip to a panel; and

Figure 7 is a view of the ventilator in section illustrating one panel narrower in 75 width than the other to produce a tight engagement with the window sill.

The ventilator comprises the extensible frame consisting of the panel members 4 and 5, which are made of any suitable character. 80 The inner ends of the panels are provided with reinforcing strips 6 on the outer face only, which permit the two members to lie close to each other, and thereby prevent currents of air from circulating therebetween. 85

As is shown, the panel members 4 and 5 are so arranged that relative movement is permitted, thereby making it possible to adjust the ventilator to various size window frames. To this end, slots 7 are provided 90 in the panel 4 preferably adjacent the inner end, and in these slots ride tension screws or bolts 8. The bolts 8 are secured in the opposite panel 5 and project through to the outer face of the panel 4. On this end of 95 the bolt 8, a thumb nut 9 is provided which allows the degree of engagement of the two panel members to be suitably adjusted.

Likewise, the panel 5 is provided with slots 10 disposed at the outer edge of the inner end, and the slot 11 disposed centrally. Tension bolts 8 and thumb nuts 9 ride in the slots 10 and 11 for the purpose above described. It will be noted that the slots 7 and 10 serve to hold together the adjoining 105 ends, while the slot 11 serves to retain together the middle portions of the panel members. This arrangement prevents bulging or warping, and increases the ease with which the panel members may be adjusted. 110

In order to facilitate this adjustment and obviate any possibility of the two panel mem-

bers frictionally binding so as to result in locking, engaging strips 12 are provided upon each inner face adjacent to the upper and lower longitudinal edges. These strips 5 are so arranged that they space the panels apart, allowing only the strips themselves to engage. The above description is that part of the device which constitutes the invention set out and claimed in my prior 10 application; but given here to make clear the general construction of the ventilator.

The particular material out of which the panels are made is immaterial so far as the invention is concerned, although material of 15 high compressibility is preferable. In order to protect the longitudinal edges of the panel members from wearing, strips 14 are employed, these being secured in any suitable way, as for instance, by taking along 20 each face, as shown in Figure 5. The material being compressible, the prongs 16 formed by tacking will sink there into and provide a secure fastening of the strips 14, which are channeled over the edges of each 25 panel.

I have shown in Figure 1, the ventilator inserted in a window frame 17. Its position in relation to the sash members is such that the opening may be varied without 30 disturbing the ventilator. It is then extended lengthwise to engage forcibly with the window frame, which results in compressing the edges of the panels. This adjustment is retained by tightening the tension bolts 9. In order that a positive grip 35 of the ventilator in the window frame is obtained, means are provided at each end which engage the window frame, having an inherently high degree of frictional or 40 gripping ability. The strip 14 extends preferably to the end of the panel along each longitudinal edge, and between these strips at each edge a similar side strip 18 is mounted. Against the strip 18 at each side 45 of the panel, a reinforcing member 19 is disposed, which functions to stiffen the panels edge and at the same time increase the engaging surface.

It will be noted that these members 19 50 protrude slightly beyond the end of the panel, and that friction material 20 is provided to encompass them in order to cover the engaging edge surface. Retaining elements 21 may be employed to lie against the 55 outer side of the friction material to hold it securely about the strips 19. Any means may be resorted to for holding the end members on the panels, though I have illustrated rivets 22 passing on through to 60 the opposite side where they are headed for maintaining them in place.

It will be noted as an advantageous 65 feature, that the edges of the friction material 20 protruding slightly from the panel member obtain in effect a larger engaging

area than that actually provided. Moreover, a perfect setting with respect to its position in the window may be had.

As will be seen in Figure 6, a novel means of securing the reinforcing strips 6 to the 70 panels, between which are interposed the strips 18, is proposed. Along the length of the reinforcing strips 6 a plurality of holes are pierced and extended into the panel 4. Wedging pins 24 are then forcibly inserted, so that the points 26 project slightly, which are trimmed off later on to obtain 75 a smooth surface.

An important feature of the invention 7 resides in cutting the lower longitudinal 80 edge of the panels in such a manner that a tight engagement is obtained with the window sill. If each of the panels are of the same width and in alignment, a crack will be left between the outer panel and the 85 window sill when the ventilator is inserted at an angle. That is to say, the panel opposite to the one facing the inclination will be raised out of engagement with the sill. To overcome this, I propose shortening the 90 width of the panel facing the inclination, which as shown in Figure 7 is panel 5, and, if necessary in order to obtain a surface 95 engagement with the sill, trimming off the edge at an angle, as indicated at 28. Thus, the lower edge of the ventilator will meet the window sill in close engagement 100 throughout its length.

From the foregoing description it is apparent that I have provided a very simple 100 and practical window ventilator which is capable of being held by friction in view of the frictional engaging end strips, these latter strips assuring a positive grip with the window frame. Any angular position 105 of the ventilator in the window frame may be had, while the lower longitudinal edge will always engage the window sill because of one panel being of less width. I do not intend to be limited to the details shown, 110 but consider that various modifications may be made without departing from the scope of my invention as claimed.

I claim:

1. In combination with a window opening, 115 a ventilator comprising an extensible frame formed of a plurality of panel members, reinforcing strips extending along the outer end and lying against the side faces of said panel members, and friction means covering 120 the edges of said reinforcing strips.

2. In combination, a ventilator adapted 125 for insertion in a window frame, said ventilator being extensible and having its edges engaging the window frame for holding it in any desired position, said edges comprising additional means protruding slightly at each side of the ventilator to obtain a substantially wide frictional surface engagement with the window frame, said means 130

permitting the holding force to react in the plane of said ventilator.

3. In combination, a ventilator adapted for insertion in a window frame, said ventilator comprising a plurality of panels carried in extensible engaging relation, reinforcing strips disposed at the outer ends of said panels, frictional material bent around said strips so as to cover the outer edge 10 thereof, and retaining members for holding one edge of said frictional material against said reinforcing strips, said retaining members lying substantially from end to end of said reinforcing strips.
4. In combination, a ventilator adapted for insertion in a window frame, the end edges of said ventilator engaging the sash
- members of the window frame, and means extending along the opposite sides of said end edges for cushioning the same against the sash members, the cushioning action of 20 said means being in the plane of said ventilator.
5. In combination, a ventilator adapted for insertion in a window frame, the end edges of said ventilator engaging sash members of the window frame, a pair of strips fastened at each end so that their outer vertical edges protrude slightly, and friction material mounted on said strips for covering 25 said outer vertical edges.

In witness whereof, I hereunto subscribe my name this 12th day of September, 1921.

ARTHUR A. CRAIG.
